BAR TABLE

Theodore E. Rath, Jr., Box 192, Encino, Calif.

Filed Jan. 25, 1960, Ser. No. 59,160

Term of patent 14 years

(Cl. D33—14)

Fig. 1 is a perspective view of a bar table showing my new design;

Fig. 2 is a top view thereof;

Fig. 3 is a side view thereof;

Fig. 4 is a sectional view taken along the line 4—4 of Fig. 3;

Fig. 5 is another side view from a position 90° from the view of Fig. 3; and

Fig. 6 is a bottom view.

The side directly opposite that shown in Fig. 1 is substantially the same in appearance as the side shown.

I claim:

The ornamental design for a bar table or similar article, substantially as shown and described.
